UNITED STATES PATENT OFFICE.

OSCAR C. CRAVER, OF PHILADELPHIA, PENNSYLVANIA.

KNIFE-SHARPENER ATTACHMENT.

Application filed July 18, 1924. Serial No. 726,700.

To all whom it may concern:

Be it known that I, OSCAR C. CRAVER, a citizen of the United States, residing at Philadelphia, in the county of Philadelphia and State of Pennsylvania, have invented certain new and useful Improvements in Knife-Sharpener Attachments, of which the following is a specification.

My invention relates to sharpening devices, and particularly to that type which employs parallel series of overlapping discs to provide a determined edge contact of the transversely moved instrument, with the peripheral edges of the discs; and my improvement consists in an attachment whereby the blades of scissors for instance may be fixedly supported as desired during the sharpening movement thereof to insure the securing of a uniformly beveled edge, as fully described hereinafter in connection with the accompanying drawings and clearly defined in the subjoined claims.

Fig. 1 is a side elevation of a sharpener having my invention applied thereto in one operative position; Fig. 2 is a plan view of the same; and Fig. 3 is a similar view to Fig. 1 showing my attachment in reverse position upon the same axle, and also indicating in dotted lines its like application to the axle of the other series of discs. Fig. 4 is a separate view of my attachment in the preferred form indicated in Figs. 1 to 3.

The known type of knife sharpener in connection with which my invention is illustrated and to which it is specifically adapted is made up of two similar series of sharpening discs; each series comprising discs, a a a or a' a' a' , which are loosely mounted with separating washers b b b , on an axle, c or c' , extending between the spaced uprights d d' of a suitable frame D . The parallel axles c c' are closed together to cause the edge portions of the discs to overlap and form an acute angled V-shaped intersection of the peripheries of the opposed discs, so that when a knife is drawn across the contacting peripheries of the discs, it is readily sharpened with a slight beveling relative to each face of the blade. Such sharpening action however is not adapted for shearing instruments in which the cutting edge is formed in the plane of one face of the blade with a single bevel extending to the other face; and the object of my invention is to provide a simple blade-

supporting attachment adapted to provide satisfactorily for such sharpening action.

As shown in Fig. 4 this blade-supporting attachment is simply formed from a piece of sheet metal bent to span a series of discs and provided with approximately parallel pivot members 1 , $1'$ each of which is apertured as indicated at 2 , $2'$, to pivotally engage one of the disc axles c or c' within the respective frame uprights d d' ; the connecting plate 3 overhanging the discs and forming an inclined blade support when one or other edge portion 3^a or 3^b thereof is swung into contact with the peripheries of the opposed series of discs, as indicated in Figs. 1 to 3. When thus positioned in connection with the two series of discs the plate 3 forms a fixed support for a shears blade 5 indicated in the drawings, whereby contact of the latter with one series of discs is prevented while the edge thereof is subjected to uniform beveling action of the other series of discs as the blade is drawn crosswise of the latter.

The angle of the uniform bevel thus insured, to the face of the blade which is supported upon the plate 3 , is positively determined by the projection of the disc-contacting edge of the latter beyond a right-angled line 6 extending from the center of the disc axle on which the attachment is pivoted; and provision is made for varying this angle by merely reversing the position of the attachment on said axle as indicated in Fig. 3,—the plate edges 3^a and 3^b being differently spaced from said line 6 so that the angle of contact with the opposed discs will be correspondingly different. The attachment may also be applied to either disc axle as indicated by the dotted showing in Fig. 3, so that one or other of the two series of discs may be used to effect the sharpening.

It will be understood that the discs may be employed in the usual manner for sharpening knives, by swinging the attachment out of the way or removing it; while scissors blades or the like may be just as readily sharpened with a single bevel of desired uniform angle, by merely throwing the attachment into service as a fixed support for one face of the blade.

What I claim is:

1. In combination with a sharpener com-

- prising two series of overlapping discs loosely mounted upon parallel axles; a supporting device arranged to span a series of discs with parallel pivot members thereof mounted upon the corresponding axle, and a connecting plate between said members either edge of which is adapted to contact with the peripheral edges of the opposed series of discs; the opposite contact edges of the connecting plate being differently projected so as to provide different contact angles, said device being reversely mountable and adapted to thereby vary the contact angle.
2. In combination with a sharpener comprising two series of overlapping discs loosely mounted upon parallel axles; a supporting device arranged to reversely span one of said series of discs and having parallel pivot members adapted to pivotally engage the corresponding axle and a connecting plate between said members either edge of which is adapted to contact with the peripheral edges of the opposed series of discs;
- the opposite contact edges of said plate being differently projected so that the plane of said plate may form different contact angles when the device is reversely positioned upon the same axle.
3. In combination with a sharpener comprising two series of overlapping discs loosely mounted upon parallel axles; a supporting device arranged to reversely span one of said series of discs and having parallel pivot members adapted to pivotally engage the corresponding axle and a connecting plate between said members one edge of which is adapted to contact with the peripheral edges of the opposed series of discs; the plane of said connecting plate being approximately at right angles to the planes of said pivot members and the opposite contact edges thereof being differently projected so as to provide different contact angles.

In testimony whereof I affix my signature.

OSCAR C. CRAVER.
